UNITED STATES PATENT OFFICE.

WILLIAM B. ZUCK, OF PHILADELPHIA, PENNSYLVANIA.

DESIGN FOR A BOX.

SPECIFICATION forming part of Design No. 30,089, dated January 31, 1899.

Application filed October 31, 1898. Serial No. 695,130. Term of patent 14 years.

To all whom it may concern:

Be it known that I, WILLIAM B. ZUCK, a citizen of the United States, residing in the city and county of Philadelphia, in the State 5 of Pennsylvania, have invented and produced a new and original Design for Boxes, of which the following is a specification, reference being had to the drawings annexed.

Figure 1 is a perspective view of a box embodying my design. Fig. 2 is a horizontal section taken through the center thereof.

My design consists of a box 1, the front of which is provided with the elliptical opening 2. The said elliptical opening has its major 15 axis considerably greater than the minor axis

and is parallel with the side edges of the front of the box and midway between the same. The surface 3 of the opening 2 is semi-circular in cross-section, as is clearly shown in Fig. 2.

Having described my invention, what I claim as new, and desire to secure by Letters Patent, is—

The design for a box, as herein shown and described.

WILLIAM B. ZUCK.
